UNITED STATES PATENT OFFICE.

ELI E. DRYDEN, OF GRAND RAPIDS, MICHIGAN, ASSIGNOR TO PHILIP MATLER AND BENJAMIN F. BURK, COPARTNERS DOING BUSINESS UNDER THE NAME OF NATIONAL SWEEPER COMPANY, OF MARION, INDIANA.

DESIGN FOR A CASING AND HANDLE FOR CARPET-SWEEPERS.

SPECIFICATION forming part of Design No. 37,175, dated October 11, 1904.

Application filed August 8, 1904. Serial No. 220,022. Term of patent 7 years.

To all whom it may concern:

Be it known that I, ELI E. DRYDEN, a citizen of the United States, residing at Grand Rapids, in the county of Kent and State of Michigan, have invented a new, original, and ornamental Design for the Casing and Handle of Carpet-Sweepers, of which the following is a specification, reference being had to the accompanying drawings, forming part thereof.

10 Figure 1 is a plan view of the sweeper-case.

Fig. 2 is a side elevation of the case and handle. Fig. 3 is an end elevation of the same.

What I claim as new, and desire to secure by Letters Patent, is—

The ornamental design for a carpet-sweeper 15 casing and handle as shown.

ELI E. DRYDEN.
